UNITED STATES PATENT OFFICE

JOHN L. DRAKE AND LE ROY L. HANDY, OF TOLEDO, OHIO, ASSIGNORS TO LIBBEY-
OWENS-FORD GLASS COMPANY, OF TOLEDO, OHIO, A CORPORATION OF OHIO

APPARATUS FOR SURFACING PLATE GLASS

Application filed June 28, 1929. Serial No. 374,403.

The present invention relates to apparatus for surfacing plate glass or other flat sheets or plates and wherein the glass is carried on a train of cars or tables beneath a series of 5 grinding and polishing machines.

It has for its primary object the provision of novel and improved means for effecting the desired movement of the cars or tables beneath the grinders and polishers. The driving means herein provided for the cars or 10 tables consists preferably of a pair of independent drives engaging said tables and normally operating simultaneously and in synchronism so that the driving load will be 15 substantially divided therebetween. However, upon the failure of either drive to operate, the other drive will take up the entire load and continue the movement of the tables so that the temporary break-down of either 20 drive will not cause the movement of the tables to be stopped. According to this invention, the two independent drives are placed in preferably close spaced relation at the rear end of the train of cars or tables so 25 as to propel them forwardly and each drive includes a drive pinion meshing with rack bars secured to the undersides of said tables. Means is also associated with each drive which will permit the drive pinion thereof 30 to idly rotate in engagement with the tables upon a failure of said drive to operate and while the other drive takes up the entire load. If desired, however, only one of the drive pinions need be positively driven at one time 35 so that the tables will be driven by a single drive and the drive pinion of the second drive permitted to run idly, being driven by the movement of the tables. Upon failure of the first drive, the second drive can be placed in 40 operation to assume the burden of moving the tables while permitting the drive pinion of the first drive to idly rotate. Another object of the invention is the provision of apparatus for mounting the drive pinions so 45 that either one of said pinions may be lowered out of engagement with the rack bars on the tables to facilitate the repairing or replacement thereof, or of other parts of the driving mechanism, without necessitating the 50 stopping of the tables.

Other objects and advantages of the invention will become more apparent during the course of the following description when taken in connection with the accompanying drawings.

55

In the drawings forming a part of this application and wherein like numerals are employed to designate like parts throughout the same,

Fig. 1 is a top plan view of driving apparatus provided by the present invention and shown in association with a train or series of tables partially broken away.

Fig. 2 is a transverse section through the overrunning clutch taken substantially on line 2—2 of Fig. 1.

Fig. 3 is a detail view partially in elevation and partially in section, said section being taken substantially on line 3—3 of Fig. 2.

Fig. 4 is a side elevation, partially in section, of the adjustable mounting for each drive pinion, and

Fig. 5 is a section taken substantially on line 5—5 of Fig. 4.

Referring to the drawings, a plurality of 75 glass sheets 10 to be surfaced and disposed end to end are adapted to be secured upon the tops of a series of movable tables 11 by the aid of a suitable plastic material 12 such as plaster of Paris or the like. A desired 80 number of tables 11 are arranged in end to end abutting relation and are adapted to be moved continuously in a definite substantially horizontal path to carry the glass sheets first beneath a series of grinding units and 85 then beneath a series of polishing units (not shown). The means herein provided for effecting the desired horizontal movement of the tables comprises the two separate drives 90 13 and 14, said drives being preferably arranged in relatively close spaced relation at the rear end of the line of tables so as to propel said tables forwardly. Inasmuch as the two drives are of the same construction and operate in the same manner, a detailed 95 description of only one will be given.

Each drive comprises a drive pinion 15 adapted to mesh with the rack bars 16 secured to the undersides of tables 11. The drive pinion 15 is arranged within a casing 17 and 100

is mounted therein upon a shaft 18 journaled at its opposite ends in the side walls of said casing. Mounted adjacent the casing 17 is a fixed support 19 including the spaced horizontal bearings 20 and 21 within which is journaled the shaft 22. Encircling the shaft within the bearings 20 and 21 are the bushings 23 and 24 respectively, said bushings projecting at their inner ends beyond the 10 bearings as indicated at 25. The casing 17 is provided at one point with a reduced extension 26 and this extension is pivotally mounted upon the inner projecting end portions 25 of the bushings 23 and 24 as clearly 15 shown in Fig. 5. Mounted upon shaft 22 and located within the reduced portion 26 of casing 17 is a spur gear 27 adapted to mesh with the drive pinion 15. Also mounted adjacent the casing 17 but in 20 a position substantially opposite that of support 19, is a stationary vertical standard 28 within which is carried the vertical lifting screw 29, said screw being adapted to support upon its upper end the lug 30 carried by casing 17 at a point substantially opposite the reduced portion 26 thereof. The lifting screw 29 has threaded thereupon a worm gear 31 and meshing therewith is a worm (not shown) but which is carried by the shaft 32 25 operated by hand wheel 33. Thus, upon rotation of worm gear 31 the lifting screw 29 will be threaded upwardly or downwardly therethrough and thus cause the casing 17 to rock upon the bushings 23 and 24 to move 30 the drive pinion 15 into or out of engagement with the rack bars 16 on tables 11. Thus, should it be desirable or necessary for one reason or another to move the pinion out of 35 engagement with the rack bars on the tables, this can be easily effected by simply rotating the worm gear 31 to cause the lifting screw 29 to be threaded downwardly therethrough. The standard 28 is provided with a stop portion 34 adapted to limit the upward movement 40 of lug 30 and this stop portion can be so located that when the lug 30 abuts the same, the drive pinion will be properly meshed with the rack bars on the tables.

Mounted in alignment with shaft 22 is a 50 shaft 35 and these two shafts are connected together by a suitable coupling designated in its entirety by the numeral 36. This coupling comprises the interlocking coupling sections 37 and 38 carried by shafts 22 and 35 respectively, the section 37 being loosely mounted on shaft 22 and the section 38 fixed to shaft 35. Associated with the shaft 22 is an overrunning clutch arrangement designated in its entirety by the numeral 39 and comprising 55 a sleeve or hub 40 keyed to shaft 22 and provided with a plurality of ratchet teeth 41 having wear plates 42 upon the flat inner faces thereof. Encircling the sleeve 40 is an annular casing 43 provided at one point 60 thereof with an attaching ear 44 secured by

suitable means 45 to a similar ear 46 formed on hub 47 loosely mounted upon shaft 22 and carried by and constituting a part of the coupling section 37. Mounted within the side walls of the casing 43 are a plurality of 65 spaced shafts 48 upon which are mounted pawls 49 adapted to engage ratchet teeth 41 and being normally urged into engagement therewith by the leaf springs 50 secured at their inner ends as at 51. The shaft 35 is 70 adapted to be driven from a motor 52 through the intermediary of suitable reduction gearing located in the casings 53 and 54 respectively.

In the operation of the present improved 75 driving means, the two drives 13 and 14 are adapted, under normal conditions, to operate simultaneously so that the drive pinions 15 thereof will be positively driven in synchronism and the driving load positively driven, 80 the shaft 22 will be rotated upon the engagement of pawls 49 with the ratchet teeth on sleeve 40, it being remembered that the sleeve 40 is keyed to shaft 22 while the casing 43 carrying pawls 49 is loosely mounted thereon and driven from shaft 35. However, due 85 to the provision of the overrunning clutches 39, each drive pinion will be permitted to idly rotate in engagement with the rack bars of the tables upon the failure of its respective 90 drive to operate or should the drive be purposely stopped for the making of repairs. Thus, should the motor 52 or the reduction gearing located in housings 53 and 54 break down and fail to properly function, or 95 should such parts need repairs and the motor 52 purposely stopped, the drive pinion 15 will be permitted to idly rotate in engagement with the tables, being driven along by the movement thereof. Upon idle rotation 100 of the pinion 15, the sleeve 40 carrying ratchet teeth 41 will be permitted to rotate with respect to casing 43 and pawls 49 which will remain stationary. Due to such an arrangement, the drive can be repaired without 105 the necessity of removing the drive pinion from engagement with the tables. Were the overrunning clutch not provided and should the drive cease to operate, the drive pinion 110 would be brought to a sudden stop and would cause a jamming of the apparatus which would stop the movement of the tables and probably cause breakage of parts of the apparatus.

It is to be understood that the form of the 115 invention herewith shown and described is to be taken as the preferred embodiment of the same, and that various changes in the shape, size and arrangement of parts may be resorted to without departing from the spirit 120 of the invention or the scope of the subjoined claims.

We claim:

1. In sheet glass surfacing apparatus, the 125 combination with a series of tables adapted

to carry glass sheets to be surfaced, of driving means for the tables including a drive pinion engaging said tables, a casing within which said drive pinion is mounted, a fixed support including spaced horizontal bearings, a shaft journaled in said bearings, said casing being pivotally mounted upon said fixed support, a gear mounted upon said shaft and in mesh with the drive pinion, means for driving said shaft to rotate the gear and pinion to effect movement of the tables, and means for raising and lowering the casing about its pivot to move the drive pinion into or out of driving engagement with said tables.

2. In sheet glass surfacing apparatus, the combination with a series of tables adapted to carry glass sheets to be surfaced, of driving means for the tables including a drive pinion engaging said tables, a casing within which said drive pinion is mounted, a fixed support including spaced horizontal bearings, a shaft journaled in said bearings, bushings encircling the shaft within said bearings and projecting therebeyond at their inner ends, said casing being provided with a reduced extension pivotally mounted upon the inner projecting end portions of said bushings, a gear mounted upon said shaft and located within the reduced portion of said casing in mesh with the drive pinion, means for driving said shaft to rotate the gear and pinion to effect movement of the tables, and means for raising and lowering the casing about its pivot to move the drive pinion into and out of driving engagement with said tables.

3. In sheet glass surfacing apparatus, the combination with a series of tables adapted to carry glass sheets to be surfaced, of a plurality of independent drives for the tables, each including a drive pinion engaging said tables, a casing within which said drive pinion is mounted, a fixed support including spaced horizontal bearings, a shaft journaled in said bearings, said casing being pivotally mounted upon said fixed support, a gear mounted upon said shaft and in mesh with the drive pinion, means for driving said shaft to rotate the gear and pinion to effect movement of the tables, an overrunning clutch associated with the drive to allow the drive pinion thereof to idly rotate in engagement with the tables, and means for raising and lowering the casing about its pivot to move the drive pinion into and out of driving engagement with said tables.

4. In sheet glass surfacing apparatus, the combination with a series of tables adapted to carry glass sheets to be surfaced, of a plurality of independent drives for the tables, each including a drive pinion engaging said tables, a casing within which said drive pinion is mounted, a fixed support including spaced horizontal bearings, a shaft journaled in said bearings, bushings encircling the shaft

within said bearings and projecting therebeyond at their inner ends, said casing being provided with a reduced extension pivotally mounted upon the inner projecting end portions of said bushings, a gear mounted upon said shaft and located within the reduced portion of said casing in mesh with the drive pinion, means for driving said shaft to rotate the gear and pinion to effect movement of the tables, an overrunning clutch associated with the drive to allow the drive pinion thereof to idly rotate in engagement with the tables, and means for raising and lowering the casing about its pivot to move the drive pinion into and out of driving engagement with said tables.

Signed at Toledo, in the county of Lucas, and State of Ohio, this 20th day of June, 1929.
